UNITED STATES PATENT OFFICE.

WILLIAM J. LANDIS, OF COLUMBUS, OHIO.

BICYCLE-HANDLE.

SPECIFICATION forming part of Letters Patent No. 496,834, dated May 2, 1893.

Application filed December 27, 1892. Serial No. 456,457. (No model.)

To all whom it may concern:

Be it known that I, WILLIAM J. LANDIS, a citizen of the United States, residing at Columbus, in the county of Franklin and State 5 of Ohio, have invented a certain new and useful Improvement in Bicycle-Handles, of which the following is a specification.

My invention relates to improvements in bicycle handles, in which an adjustable handle 10 for guiding the machine when in operation, takes the place of a stationary or fixed handle, enabling the rider to comfortably occupy different and desired positions when riding. I attain this by the mechanism illustrated in 15 the accompanying drawings, in which—

Figure 1. is a front view, and Fig. 2. is a side view.

A, is a T connection, with a tubular excavation B in its upper part, wherein the metallic handle is inserted and made secure thereto by brazing. A may be cast, or it may be made from a solid piece of metal by drilling or milling therein the hole B to such a diameter as will neatly admit the circumference 25 of the bar forming the handle.

C is a fulcrum-screw by which the different angles of the bar are arrived at, and is constructed as a double-screw that the lost motion occurring from constant use may be 30 easily taken up.

D is a plunger, operated vertically by means of the threaded screw E.

F is a coil or spiral spring, which makes the plunger D work automatically and keeps it in 35 the desired stationary position.

H is a circular-swivel with a number of notches L in its surface into which the plunger D enters and fits, thereby locking itself when the desired angle is arrived at.

I is an excavation or hole in the circular-swivel H by which it is fulcrumed on the screw C.

J is a tubular upright, connected with the body of the circular-swivel H by being brazed and made secure thereto at the line K.

By the mechanism shown, I place the handle of a bicycle at such an angle as will be found desirable to the rider, at the same time enabling him to adjust the bar to such an angle as will, from time to time, suit his position.

Having fully described my invention, what I claim, and desire to secure by Letters Patent, is—

A handle-bar for a bicycle, consisting of a T connection, a plunger, a fulcrum screw by 55 which different angles are arrived at, and a circular - swivel containing one or more notches by which the angles are made secure and positive, substantially as set forth.

In testimony that I claim the foregoing as 60 my invention I have signed my name, in presence of two witnesses, at Columbus, Ohio, this 23d day of December, A. D. 1892.

WILLIAM J. LANDIS.
